STOCK FASTENING MEANS

David E. Bost, Galesburg, Ill.

Application August 10, 1938, Serial No. 224,189

4 Claims. (Cl. 42—75)

This invention relates to guns, and more particularly to a means for changing the angular relation or pitch of the gun barrel relative to the gun stock.

An object of this invention is to provide means insertible between the forward end of the gun stock and the rear end of the breech whereby the angular relation of the gun barrel relative to the stock may be changed to suit the desires of the individual user of the gun.

Another object of this invention is to provide a means in the form of a shim which is adapted to be inserted between the gun stock and the breech so that if desired the angular relation of the barrel and the stock may be changed, or the position of the barrel relative to the gun stock may be varied by moving the gun barrel forwardly.

A further object of this invention is to provide an insertible member adapted to be inserted between the gun stock and the barrel for changing the position or angular relation of the two parts relative to each other without the necessity of materially changing either of these parts so that an ordinary mechanic may easily and quickly change the position of the gun barrel as to the gun stock, the device being so formed and constructed that if desired the original relation of the two parts of the gun may be restored.

To the above ends essentially and to others which may hereinafter appear, the system consists of the novel construction, combination and arrangement of parts as will be more specifically referred to and illustrated in the accompanying drawing wherein is shown an embodiment of the invention, but it is to be understood that changes, variations and modifications may be resorted to which fall within the scope of the invention as claimed.

In the drawing:

Figure 1 is a detail side elevation of a gun including a barrel and a stock having a pitch changing device constructed according to an embodiment of this invention interposed between the breech and the gun stock.

Figure 2 is an enlarged fragmentary longitudinal view of the forward end of the gun stock and the rear end of the breech showing the manner of applying the improvement to the gun.

Figure 3 is a detail front elevation of the device removed from the gun.

Figure 4 is a detail rear elevation of this device, and

Figure 5 is a detail side elevation of the device.

Referring to the drawing, the character G

designates generally a gun including a barrel B provided with a breech 10 to which is secured a gun stock 11. The gun herein disclosed is a conventional shot gun of the repeater type and it will be understood that the hereinafter disclosed pitch changing device may be applied to guns of various types including pistols, wherein it is desired to change either the angular relation of the gun barrel relative to the gun stock, or to lengthen the gun stock so as to move the breech forwardly the desired distance.

In the manufacture or production of guns a substantial standard is used as to the length of the stock, so that the breech and the rear end of the barrel will be positioned at the desired distance where the barrel is in proper alignment with the eye for the purpose of sighting along the barrel. Where a special gun stock is manufactured the correct position of the barrel B and the breech 10 may be readily determined.

However where the gun or firearm is manufactured according to a predetermined standard, the position of the barrel B is frequently inconvenient to a particular user, and it is necessary for a gun-smith to either produce a new gun stock where the stock should be longer, or to cut off the old stock where it is necessary to shorten the original or standard stock. Where it is desired to increase the length of the gun stock, it has been the practice to cut the gun stock at an intermediate point and then insert a spacer member at such intermediate point, but this procedure involves considerable expense and requires the services of an expert.

In order, therefore, to provide a means whereby the stock 11 may be lengthened, or the pitch of the barrel B may be varied without cutting of the stock 11, I have provided a plate 12 in the form of a shim which is adapted to be inserted between the rear end of the breech 10 and forward end of the stock 11. This plate 12 has a configuration in front elevation similar to the configuration of the rear end of the breech 10 being of substantially oval configuration so that the marginal portions of this plate 12 are flush with the outer surfaces of the stock 11 and the breech 10.

In side elevation the plate 12 may be provided with one surface 14 thereof which is disposed on an angle to the other or rear side 15 thereof. The rear side 15 is adapted to abut against the forward end of the stock 11 and the front side 14 is adapted to abut against the rear end of the breech 10. The angle between the front side 14 and the rear side 15 may be varied depending upon the change which it is desired to make be-

- 5 between the angular relation of the barrel B and the gun stock 11. In the present instance the wider portion of the plate 12 is lowermost so that the angle between the barrel B and the stock 11 is increased, but it will be understood that if desired the wider portion of the plate 12 may be at the upper end thereof where it is desired to decrease the angular relation of the barrel B relative to the stock 11.
- 10 The plate 12 is provided on its forward side with a substantially annular rib or bead 16 which is adapted to engage in an annular socket 13 provided in the rear end of the breech 10. In the present instance the breech 10 is provided with a rearwardly extending lug 17 having a threaded opening 18 for receiving a bolt 19 which extends through a rearwardly extending lug 20 provided in a portion of the breech mechanism 10. The plate 12 is provided with an axially or centrally disposed opening 21 and a slot 22 extends from the opening 21 and communicates with a relatively larger slot 23 in which the lug 20 is received.
- 15 The rear side 15 of the plate 12 is provided with an annular recess or socket 24 in which is received an annular bead 25 formed in the forward end of the gun stock 11. A rearwardly extending sleeve 26 is carried by the breech 10 and is provided with a threaded bore 27. This sleeve 26 engages in a bore 28 provided in the gun stock 11, and a bolt 29 is threaded into the sleeve 27. The bolt 29 is provided with a head 30 having a kerf 31, and the forward side of the head 30 is provided with a convex or rounded surface 32.
- 20 35 A washer 33 is disposed about the bolt 29 and is provided with a concave seat 34 to receive the convex head 30 so that when the angular relation of the stock 11 is varied from the breech 10, the bolt 29 may automatically adjust itself, and the head 30 of the bolt will snugly seat on the washer or plate 33. A spring washer 35 is interposed between the seat member 33 and a shoulder 36 provided interiorly of the gun stock 11 at the rear end of the bore 28.
- 30 40 45 In the use of this device, where it is desired to change the angular relation between the barrel B and the stock 11 and the angular relation is increased, the plate 12 is formed as shown in Figures 1 and 2 with a wider portion lowermost and with the outer face 14 thereof inclined at the desired angle relative to the inner face 15. The gun as originally produced includes the bolt 29 having a flat head and this bolt is then either replaced by a bolt having a head convex at its forward side or the head of the original bolt is rounded off so as to provide the convex portion 32.
- 50 55 60 A washer 33 is then mounted about the bolt 29 so that the convex head 32 will snugly seat on the seat 34 of the washer 33. The bore 28 of the stock 11 may require a slight reaming out so that the sleeve 26 may adjust itself in the bore 28 to the new angle between the stock 11 and the breech 10. This reaming out of the bore 28 is the only change which is required in the original stock 11. No other change is necessary in the stock 11 nor in the breech 10. The plate 12 is provided with the bead 16 on its forward side and with a socket or annular groove on its rear side to conform to the connection between the original stock 11 and the breech 10.
- 65 70 75 It will be understood that this head connection will probably be varied depending on the particular configuration of the connection between

the stock 11 and the breech 10 in various types of firearms.

Where it is desired only to move the barrel B forwardly a slight distance without changing the angular relation of the barrel B relative to the stock 11, the plate or shim 12 will have parallel front and rear sides. Where it is desired to reduce the angle between the barrel B and the stock 11, the plate 12 will have a wider upper edge than the lower edge, this angle being determined in advance in accordance with the desire of the user of the gun.

In the event it should be found desirable at a later date to restore the gun G to its original condition, this may be done easily and quickly by loosening the bolt 29 and removing the plate 12. The bead 26 at the forward end of the stock 11 will then seat directly in the annular groove 13 at the rear of the breech 10.

This device may be manufactured at a relatively small cost and may be applied either by the user of the gun or by a mechanic who is not particularly skilled in the manufacture or repair of guns. It will be seen therefore that a gun manufactured after a well-known standard can easily and quickly be changed or individualized to suit the desires of a particular user in order that the gun barrel will be in the position desired by the particular user.

It is well known that expert riflemen usually require considerable changes in guns after the manufacture of the guns, and heretofore such changes have been an expensive proposition and have required the services of an expert gunsmith. These changes usually take the form of variation in the angular relation between the gun barrel and the gun stock, or take the form of an increase in the length of the gun stock so as to move the breech or rear end of the gun barrel further away from the standard gun stock.

With the use of this device the standard gun can easily and quickly be individualized and at a relatively small cost, the change in the gun being of such a character that if desired the gun can easily and quickly be brought back to its original standard condition.

What I claim is:

1. A means for varying the angular relation between a gun barrel having a breech at the rear end thereof and a gun stock, comprising a plate tapering in thickness from one edge to an opposite edge, the opposite faces of said plate having a configuration coincident with the joint between the breech and stock, said plate being positionable between the breech and stock.

2. As a new article of manufacture a pitch varying device for varying the pitch of a gun barrel relative to the gun stock comprising a wedge-shaped plate engageable between the barrel and the stock, an annular bead on one face of said plate engageable in an annular groove provided in the rear end of the barrel, the opposite face of said plate having an annular groove to receive an annular bead carried by the gun stock.

3. A means for varying the angular relation between the rear end of a gun barrel and a gun stock, comprising a plate tapering in thickness from one edge to an opposite edge and adapted to be interposed between the rear end of the barrel and the gun stock, the opposite faces of said plate having means engageable with the barrel and the stock to hold the plate against lateral movement.

4. A means for varying the angular relation

between the rear end of a gun barrel and a gun stock, comprising a plate tapering in thickness from one edge to an opposite edge and adapted to be interposed between the rear end of the barrel and the gun stock, the opposite faces of said plate having means engageable with the barrel

and the stock to hold the plate against lateral movement, said plate having a central opening therethrough and a radially disposed slot extending from said opening to an edge of the plate.
